UNITED STATES PATENT OFFICE.

JOHN ROGERS FLANNERY, BENJAMIN E. D. STAFFORD, AND ETHAN I. DODDS, OF PITTSBURGH, PENNSYLVANIA, ASSIGNEES TO FLANNERY BOLT COMPANY, OF PITTSBURGH, PENNSYLVANIA.

STAY-BOLT STRUCTURE.

1,275,892.

Specification of Letters Patent. Patented Aug. 13, 1918.

Application filed October 25, 1917. Serial No. 198,481.

To all whom it may concern:

Be it known that we, JOHN R. FLANNERY, BENJAMIN E. D. STAFFORD, and ETHAN I. DODDS, citizens of the United States, and residents of Pittsburgh, in the county of Allegheny and State of Pennsylvania, have invented certain new and useful Improvements in Stay-Bolt Structures; and we do hereby declare the following to be a full, clear, and exact description of the invention, such as will enable others skilled in the art to which it appertains to make and use the same.

This invention relates to improvements in staybolt structures and more particularly to means for denoting the condition of staybolts for boilers,—the object of the invention being to provide means whereby an attendant may, upon inspection of said means, ascertain the condition of the bolt.

With this object in view the invention consists in certain novel features as herein-after described and pointed out in the claims.

In the accompanying drawings, Figure 1 is a sectional view representing an embodiment of our invention. Fig. 2 is a detail view, and Fig. 3 is a view of a slight modification.

1 represents a staybolt having a tell-tale bore 2 and the inlet end of this bore may be slightly tapering, as indicated at 3.

A tube or container 4 is located within the bore 2 and made preferably slightly less in diameter than the diameter of said bore so that, in the event of rupture of the bolt, moisture entering the bore may find its way into the tube through perforations 5 in the walls thereof.

The tube 4 is supported within the bore 2 by means of a plug 6 of suitable material, such as refractory element similar to clay, to which said tube is attached and said plug serves as a closure for the tube and also for the tapering end of the bore 2 of the bolt.

The tube 4 contains (under normal conditions) a quantity of soluble material 7, such, for example, as salt.

Under normal conditions when the bolt is whole, inspection of the material in the tube 4 (which latter may be readily removed from the bolt for this purpose) will disclose the material therein in crystalline form or in

solid form and thus denote that the bolt 55 is in good condition.

Should a rupture occur in the bolt which would permit the entrance of moisture into the tube 4 through the perforations 5 and 60 dissolve the material 7 contained within said tube. If the tube be now inspected it will be found to contain little or no crystalline or solid material and this fact will denote the ruptured condition of the bolt. 65

Instead of providing the tube 4 with numerous perforations as shown in Figs. 1 and 2, we may employ a tube 8 bent up from a piece of flat imperforate metal and formed with an elongated slot or opening 9, as 70 shown in Fig. 3, through which the moisture entering the bore 2 of the bolt may pass into the tube 8.

Having fully described our invention what we claim as new and desire to secure 75 by Letters-Patent, is:

1. The combination with a stay bolt having a tell-tale bore, of a container removably supported within said bore and in communication therewith, and soluble material 80 within said container.

2. The combination with a staybolt having a tell-tale bore, of a tube within said bore and communicating therewith, means for removably supporting said tube and 85 closing the end of the bore, and soluble material within said tube.

3. The combination with a staybolt having a tell-tale bore, of a plug normally closing said bore and removable therefrom, a 90 perforated tube supported by said plug and disposed within the bore of the bolt, and soluble material within said tube.

4. The combination with a staybolt having a tell tale bore, a removable container within 95 the bore, a soluble material in the container and a removable plug for closing the outer end of the bore.

In testimony whereof, we have signed this specification in the presence of two sub- 100 scribing witnesses.

JOHN ROGERS FLANNERY.
BENJAMIN E. D. STAFFORD.
ETHAN I. DODDS.
